UNITED STATES PATENT OFFICE

JOSEPH ANNICK, OF RENAIX, BELGIUM

DEVICE FOR TREATING FABRICS BY MEANS OF A CIRCULATING BATH

Application filed June 19, 1931, Serial No. 545,538, and in Belgium May 2, 1931.

My present invention has for its object to provide an improved device or vat for treating fabrics in pieces by means of a circulating bath, for instance for dyeing, bleaching, sizing or similarly treating fabrics. More particularly my invention has for its object to secure in any circumstance a perfect and uniform impregnation of the entire mass of fabric. Such result could not be attained heretofore, because under the influence of the pressure of the bath the spool of fabric impregnated with liquid was subject to certain distortions in opposite directions according to the direction of circulation. If the bath is circulating from outside to inside of the spool, the latter has tendency to become contracted: the ends of the spool will be curved inwardly and the major part of the bath then passes between said ends and the caps which embrace the spool. In the opposite direction of circulation the spool has tendency to become wider and to be curved towards the centre.

Heretofore spool cores have already been known for balancing or compensating the effects of such expansion and contraction of the spools. According to a preferred embodiment said spool core is formed of a coil spring, covered by a practically continuous surface formed by tressing or platting a lace, textile, metallic or other thread or fabric around the successive windings of the spring. Such core secures a uniform expansion and contraction of the spool, that is the opposite plane faces of the spool will always remain substantially parallel to each other without forming undesirable passages for the bath.

If it is desired to treat fabrics in pieces wound in the shape of spools, the effect of such a spool core will however be insufficient as hereinafter set forth. In said treatment the thick spools are placed upon a supporting plate and held in a tightened condition prior to the treatment thereof by means of an upper plate. Now if under the action of the bath the impregnated spool contracts itself, it will enable the liquid to pass between said plate and the upper surface of the spool, which objection will precisely be avoided by my present invention. If the upper cap or plate is left free to be moved vertically, liquid

passages will be undoubtedly formed, upon the raising of said cap under the action of the expansion of the spool, between the plate and the spool, the regulating action of the elastic core being not perfectly uniform. 55

According to my present invention, I combine with an elastic spool core of the type described a cap or upper plate which is provided on its side in contact with the spool of fabric with projecting ribs to thereby prevent an unduly active circulation of the liquid between the edge of the fabric and said plate. 60

The invention is illustrated in the accompanying drawing showing one preferred embodiment of the invention, in which drawing: 65

Fig. 1 is a vertical sectional elevation of a vat with a spool mounted in place.

Fig. 2 is an enlarged view of the click and dog mechanism. 70

Figs. 3 and 4 are front views of an elastic spool core during the formation thereof and upon the finishing thereof respectively.

Referring to the drawing and more particularly to Figs. 1 and 2, 1 designates the vat, 75 for instance a dyeing digester, provided with a central conduit 2 and a lateral conduit 3 for causing the circulation in both directions: from the centre to the periphery and in opposite direction. The conduit 2 is connected to the vertical perforated central tube 4 in the vat. 5 is the spool of fabric, formed around a core 6. Said core is of the elastic type, that is formed of a coil spring 6' covered with a practically continuous surface formed 80 by tressing or platting a lace 6'', textile, metallic or other thread of fabric around the successive windings of the spring. (See Figs. 3 and 4). The whole of the spool and core is fitted upon the central tube 4. 85 The spool is supported on a stationary lower plate 7 and pressed upon the latter by means of a heavy upper plate or cap 8. Said cap has a hollow hub member 9 fitted on a rod 10 forming the extension of the central tube 4. Said rod is made of square or circular cross section and formed with rack teeth on its entire length. The rod 10 extends loosely through a central hole in the bottom of the hub member 9, which carries a series of piv. 95 100

oted pawls 11, 11' . . . , the noses of which engage the rack 10. As shown in the example, said pawls are preferably displaced with relation to each other, that is (Fig. 2) if the 5 pawl 11 engages the rack, the remaining pawls 11', 11'', 11''' . . . will be located respectively to $\frac{1}{4}$, $\frac{1}{2}$, $\frac{3}{4}$ . . . of a tooth lower, so that upon the lowering of the cap 8 to $\frac{1}{4}$ of tooth, the pawl 11''' will engage the cor- 10 responding tooth of the rack.

It will be seen that if the various parts are in the positions shown in Fig. 1, the raising of the cap 8 is rendered impossible owing to one of the pawls 11 engaging the rack 10. 15 However the lowering of said cap is permitted and even facilitated by the weight of said cap. Therefore as soon as under the action of the bath circulating from the periphery to the centre the spool tends to be contracted, the cap 8 will follow such movement and be lowered to $\frac{1}{4}$, $\frac{1}{2}$ or more of a tooth, one of the pawls 11 always remaining engaged in order to prevent the cap 8 from being moved upwardly upon the reversing 25 of the direction of circulation. Therefore the longer the treatment is continued, the more the cap 8 will have tendency to be lowered and the more the fabric will be compressed, and what is important the higher 30 will be the resistance to the passage of the bath between the spool and plates 7 and 8.

It will be obvious that it is not necessary that the different pawls work precisely to $\frac{1}{4}$ of tooth as described. According to the 35 height of the rack teeth, said pawls may be caused to work to $\frac{1}{3}$, $\frac{1}{6}$ etc. of tooth. Again in order to avoid any false bearing, the cap 8 will be preferably provided, as shown in the drawings, with a plurality of series of 40 pawls, so that there will always be at least two, three or four pawls in simultaneous engagement at points which are symmetrically arranged on the periphery of the rack.

As already described the resistance opposed 45 to the passage of the bath between the spool and plates 7 and 8 increases with the duration of the treatment. In order to secure a sufficient resistance already at the beginning of the treatment, I have provided concentric 50 ribs 12 on both plates 7 and 8. Under the pressure said ribs 12 will be pressed into the spool and thus prevent the liquid from passing.

Having now fully described my said invention, what I claim and desire to secure by Letters Patent, is:

1. In a device for dyeing, bleaching, sizing and similarly treating fabric wound in the shape of a spool, the combination of a vat, a 60 central perforated tube within said vat, a conduit connected to said central tube, a second conduit issuing laterally into said vat, a lower stationary supporting plate for the spool of fabric within the vat, a movable 65 upper pressure plate engaging the top of the

spool of fabric under treatment, a hub member formed on the top of said upper plate, a central hole in the top wall of said hub member, a vertical rod formed with rack teeth extending from the top of the central perforated tube through the central hole in the top wall of the hub member, series of pawls pivoted on said hub member and engaging the rack teeth on said rod, said pawls being arranged in such a way that in any position of the hub member at least one pawl will engage the rack, whereby the upper plate will be enabled to be moved downwardly and prevented from being moved upwardly, and circular concentric ribs formed on the upper side of the lower supporting plate and the lower side of the upper pressure plate respectively, substantially as and for the purpose set forth.

2. In a device for dyeing, bleaching, sizing and similarly treating fabrics in a spool by means of a circulating bath, the combination with a spool of fabric formed around an elastic core comprising a coil spring covered with a continuous surface formed of a tressing, a lower stationary plate for supporting said spool, an upper, downwardly movable plate provided with pawls preventing upward movement of said plate, said upper and lower plates being provided on their sides in contact with the spool with ribs affording resistance to the passage of the liquid between the ends of the spool and said plates.

JOSEPH ANNICK.
